UNITED STATES PATENT OFFICE.

VERNON ROSS, OF KANSAS CITY, MISSOURI.

STORE-FRONT CONSTRUCTION.

1,024,420.

Specification of Letters Patent. Patented Apr. 23, 1912.

Application filed March 7, 1910. Serial No. 548,304.

To all whom it may concern:

Be it known that I, VERNON Ross, a citizen of the United States, residing at Kansas City, in the county of Jackson and State of Missouri, have invented certain new and useful Improvements in Store-Front Constructions, of which the following is a specification.

This invention relates to store front constructions and more particularly to what is known as a division bar or mullion for securing together the adjacent edges of two window plates, and my object is to produce a division bar by which the window plates can be efficiently and reliably held without danger of breaking or chipping the glass and which is of simple, strong, durable and inexpensive construction.

A further object is to produce a division bar composed of parts susceptible of being bent to different forms to accommodate window plates arranged in the same plane or at different angles to each other, the division bar acting as a corner bar where the glass plates are disposed at an angle to each other.

With these objects in view and others as hereinafter appear, the invention consists in certain novel and peculiar features of construction and organization as hereinafter described and claimed and in order that it may be fully understood reference is to be had to the accompanying drawing, in which—

Figure 1, is a perspective view of a part of a window front in which the glass plates are connected together at their adjacent edges by a division bar embodying my invention. Fig. 2, is a central vertical section on the line II—II of Fig. 1. Fig. 3, is a horizontal section in the plane of the line III—III of Fig. 2, but with certain parts bent to different form so as to act as a corner bar.

Referring now to the drawing in detail where like reference characters identify corresponding parts in all the figures, 1 indicates a pair of glass plates arranged in the same plane as in Fig. 1, or at an angle to each other as shown in Fig. 3, or at any other suitable angle.

2 indicates the front clamping member, the same comprising a central portion 3, and a pair of lateral extensions or hooks 4, the terminals of the hooks being disposed inward of their body portions and arranged

to bear squarely against the front or outer faces of the glass plates and said front member is preferably of copper, bronze or brass.

At suitable points along the length of the front bar are reinforce members 5, one only being shown, and each reinforce plate is preferably constructed of galvanized steel and consists of a perforated body portion 6, arranged inward of and spaced from and acting as a bridge for the body portion 3 of the front clamping member and a pair of flanges 7 which engage the hooks 4 of said clamping member.

Arranged at the inner sides of the glass plates and bridging the space between them is the rear clamping member 8, the same being preferably of copper, bronze or brass, and consisting of the inwardly bowed body portion 9, reversely bent near its vertical margins to form shoulders 10 and terminating in outturned angle flanges 11 to bear against the inner faces of the glass plates with a yielding pressure so as to accommodate expansion and contraction of said plates or to accommodate plates of slightly different thickness and said body portion 9, is provided at suitable points with holes 12, only one appearing, for a purpose which hereinafter appears.

13 indicates what I term the rear reinforcing member, the same being of substantially-U-form in cross section, and consisting of a perforated body portion 14, and a pair of forwardly projecting arms 15, the front edges of the arms being adapted to engage the shoulders 10 and be prevented thereby from spreading apart, the body portion 9 preventing inward movement of said arms.

16 indicates a headed bolt extending rearwardly through each front reinforcing member 5, an alined hole 12 of the rear clamping member 8, and an alined perforation of the body portion of the rear reinforcing member, and engaging each of said bolts and the rear side of the rear clamping member is a clamping nut 17, the nut and bolt being utilized to clamp the window plates firmly and reliably together without interfering with the contraction and expansion thereof and a nut 18 engages the rear end of each bolt 16, for the purpose of stiffening the rear clamping member and preventing any part of it yielding except the flanges 11.

When the division bar is to be used as a corner bar the various bars and plates are bent to slightly different form, that shown

in Fig. 3, representing what is known as a "reverse corner," it being obvious that the parts may be bent to accommodate an obverse corner, if desired.

5 From the above description it will be apparent that I have produced a division bar for store front constructions embodying the features of advantage enumerated as desirable in the statement of the object of the 10 invention and susceptible of modification in minor particulars without departing from the spirit and scope of the appended claim.

Having thus described the invention what I claim as new and desire to secure by Letters Patent is:—

20 A store front construction, comprising a pair of glass plates, a front clamping member overlapping adjacent edges of said plates at their front sides and formed at its side edges with rearwardly-turned inwardly-opening hooks, a rear clamping member arranged rearward of the front clamping member and at the opposite side,

25 of said plates and consisting of a central arched portion formed at its side margins with shoulders and resilient flanges, the latter engaging the rear faces of said plates, a front reinforce member bridging the space between the glass plates and fitting at its side edges in the hooks of the front clamping member, a rear reinforce member engaging the shoulders of the rear clamping member, a headed bolt extending through the reinforce plate, the rear clamping member and the rear reinforce member, a nut 30 engaging said bolt and the rear side of the rear clamping member, and a nut engaging said bolt and the rear side of the rear reinforce member.

35 In testimony whereof I affix my signature, in the presence of two witnesses.

VERNON ROSS.
